PLUGBOARD ASSEMBLY
Akin Aksu, Harrisburg, Pa., assignor to AMP
Incorporated, Harrisburg, Pa.
Filed Jan. 11, 1963, Ser. No. 250,815
4 Claims. (Cl. 339—18)

This invention relates to improvements in plugboard devices of the type used to program electronic computers, office equipment and the like.

In U.S. Patent No. 2,975,395, issued March 14, 1961, to G. C. Sitz, there is described a specialized electrical switch or multiple connector known in the art as a plugboard or patchboard. The Sitz type assembly includes a rear bay carrying a matrix of contact spring members and a front bay carrying a complementary matrix of contact pin members. The frame of a rear bay includes a hinge mechanism fastened at the bottom thereof adapted to receive and secure a front bay and upon closure operate to cam the front bay upwardly driving pin members into contact with spring members in a particular movement of closure providing good electrical contact between pin and contact members. Through this operation sub-components of electronic systems may be selectively interconnected through paths leading to rear bay spring members in contact with front bay pin members interconnected in pairs by patchcords. As taught in the Sitz patent, a front bay may be removed and reinserted with different patterns of patchboards to define distinctive electronic system programs by interconnection of different electronic components.

In certain instances wherein there is no need for speed or wherein programs are infrequently changed, only a single front bay is provided; the front bay being withdrawn, manually reprogrammed and reinserted when the occasion arises. In other instances, circumstances may dictate the provision of ten or twelve front bays which can be, alternatively, rapidly placed into a given rear bay and driven to provide a different program.

In both the above mentioned situations, it is highly desirable to avoid final closure of bays until exactly the proper moment when system component interconnection is required. It is equally important that no accidental opening occur once a front bay has been installed and closure effected. As a further requirement, it should not be possible to insert or withdraw a front bay from a rear bay assembly until and unless the camming mechanism thereof is in the proper position where pin and spring members have relative free travel so as not be damaged by striking each other.

While the type of assembly shown in the Sitz patent meets the foregoing requirements quite satisfactorily with respect to small or medium size plugboards, a new plugboard assembly of simpler construction has been developed which is particularly well adapted for larger sizes wherein one or several thousand contact paths are provided. It is a principal object of this invention to provide a novel latch mechanism in combination with this newly developed plugboard assembly.

It is a further object of invention to provide a novel latch mechanism for plugboard assemblies operable to prevent accidental opening or closing of the contact carrying bays thereof.

It is another object of invention to provide a simple and reliable mechanism within the rear bay of a plugboard assembly adapted to both latch and lock a front bay therewithin.

Other objects and attainments of the present invention will become apparent to those skilled in the art upon a reading of the following detailed description when taken in conjunction with the drawings in which there is shown and described illustrative embodiments of the in-

2

vention; it is to be understood, however, that this embodiment is not intended to be exhaustive nor limiting of the invention but is given for purposes of illustration in order that others skilled in the art may fully understand the invention and the principles thereof and the manner of applying it in practical use so that they may modify it in various forms, each as may be best suited to the conditions of a particular use.

In a typical embodiment of the assembly of the invention there is included a plugboard rear bay carrying contact spring members centrally positioned in a surrounding open faced frame adapted to receive a front bay carrying contact pin members interconnected by patchcords. The frame of the rear bay is slotted at the top to accommodate pivot members integral with the front bay such that the front bay may be mounted in a hinged relationship to swing into the face of the rear bay. The rear bay includes at the bottom thereof a camming mechanism adapted to be operated to drive the front bay upwardly carrying the pin members thereof into engagement with the spring members of the rear bay to effect interconnection of desirable circuit paths.

Further included in the rear bay in each side of the frame member at the bottom portion is a latch mechanism adapted to receive and secure a front bay through cooperation with latch pins integral with the bottom sides thereof. The positioning of each latch mechanism relative to the latch pins is such that upon first closure of the front bay each latch mechanism will be cammed upwardly and then returned downwardly by spring pressure to hold the front bay in position within the frame of the rear bay. Further provided as part of each latch mechanism is a feature limiting the upward travel such that once the front bay has been cammed upwardly each latch mechanism is then locked to preclude withdrawal of the front bay until after operation of the camming mechanism to drop the front bay to the initial position following installation.

The specific characteristics of the invention, as well as other advantages thereof, will be more fully brought out from the following description taken in conjunction with drawings including:

FIGURE 1, showing perspective of a plugboard assembly having a portion sectioned to reveal the latching mechanism of the invention;

FIGURE 2, showing an exploded view of the latching mechanism of the invention;

FIGURE 3, showing a sectional plan view of the locking mechanism of the invention; and

FIGURES 4-7, showing elevations of the latching mechanism of invention in various positions of operation relative to the movement of the latch pin of a front bay.

FIGURE 1 depicts a plugboard assembly 10 including a rear bay 12 having a front bay 38 mounted therein in an initial position of installation. Carried in rear bay 12 is a matrix of contact spring members 14 secured in four insulating panel members 15 rigidly secured to frame members 16, 18, 20 and 22. Contact spring members 14 and panel members 15 are of the type shown in the above mentioned Sitz patent. Frame members 16, 18, 20 and 22 are of milled stainless steel or aluminum bar stock suitably secured at their ends by screws, rivets or the like. To the rear of bay 12 and not shown, individual electrical conductors are secured to each of the contact spring members forming signal paths to and from various electronic components sought to be interconnected by operation of assembly 10.

Supported by and secured to cross pieces 22 of the frame is a bearing support 24 centrally disposed to carry cam members 26 at one end thereof. The other ends of members 26 are carried by a bearing surface in the lower

portion of side pieces 16 and 18 of frame 12 and include extensions through such side pieces to engage cam arms 30 and 34 as indicated by numeral 28 with respect to arm 30. Cam arms 30 and 34 are locked to cams 26 and rotation of arms 30 and 34 will operate to drive cam members 26 in an identical rotary movement. Arms 30 and 34 are shown in FIGURE 1 in the fully opened position; the fully closed position being parallel to frame side pieces 16 and 18 with the upper face of each arm resting against the offset on each side piece indicated by numeral 17 with respect to side piece 16. Handles 32 and 36 are useful in rotating arms 30 and 34 downwardly from the closed position.

Adapted to be positioned within frame 12 is a front bay 38 having a rigid frame 40 mounting four insulating panel members 42 apertured as at 43 to receive pin assemblies interconnected in pairs by patchcords such as 45. Frame 40 may be comprised of stainless steel or aluminum stock suitably milled to accommodate panels 42; or as in the preferred construction shown in FIGURE 1 may be comprised of an interior frame of flock filled phenolic resin member 46 surrounded by stainless steel bar members 47. At opposite corners secured to the vertical members of frame 40 are projecting pin members; the upper pin members (not shown) being similar to lower pin members 52 and 54. Also attached to the side pieces of frame 40 are handle members 48 employed to lift and manipulate front bay 38.

Located at the bottom interior of rear bay 12 are latch mechanisms 66 and 68 positioned in slots 62 and 64 of side pieces 16 and 18. As shown in FIGURE 1, the latch mechanisms are set back into side pieces 16 and 18 so as to provide free travel of frame 40 of 38 into the face of 12. Each mechanism 66 and 68 is positioned so as to be engaged by one of the pin members 52 and 54 as 38 is closed into 12.

Operation of assembly 10 calls for an initial placement of front bay 38 as shown in FIGURE 1 with the upper pin members resting in pivotal relationship within slots in plate members 19 and 21 set into the side pieces 16 and 18 of 12. Following this initial placement, front bay 38 may be swung downwardly and into the face of rear bay 12 pivoted on the upper pin members. As 38 enters the face of 12, pin members 52 and 54 engage the lower forward surfaces of each latch mechanism 66 and 68, respectively, driving such upwardly to be returned under spring pressure in a manner to be described more fully hereinafter. With 38 fully seated within 12, latch mechanisms 66 and 68 serve to hold 38 within the face of 12 by holding pin members 52 and 54 against withdrawal. Because of this, front bay 38 is latched against outward movement regardless of the attitude of assembly 12 and even in the presence of jars, shocks or substantial gravitational forces applied to assembly 10 through the displacement of the vehicle, craft or other housing in which assembly 10 is situated. Furthermore, with front bay 38 latched by assemblies 66 and 68, a proper alignment of 38 is assured with respect to cams 26. With 38 in the closed position, arms 30 and 34 may be rotated upwardly to drive cams 26 into engagement with the lower surface 39 of frame 40 and thereby drive the pin members of the front bay into a particular wiping contact with the spring members of the rear bay to perform a given programming function in the same manner as taught in the Sitz patent. As will be apparent from the description further to be given, with arms 30 and 34 in the upward position and the spring and pin members inclosure, front bay 38 is locked within 12 and cannot be withdrawn therefrom until arms 30 and 34 and cams 26 have been rotated to place the assembly in the open position. This feature precludes accidental damage to either pin or contact spring members through premature attempts to withdraw the front bay from the rear bay.

Mechanisms 66 and 68 thus operate to both latch front bay 38 within rear bay 12 before interconnection of circuit paths is called for and, following interconnection,

further operate to lock front bay 38 within rear bay 12. When 38 is latched within 12 it may be withdrawn by pulling on handles 48 in a sharp outward movement. When assembly 38 is locked within 12, no amount of pulling or other force will operate to move 38 with respect to 12.

Considering now the latching mechanisms of the invention in greater detail, FIGURE 2 shows the assembly 66 exploded relative to slot 62 of side piece 16. Latching mechanism 68 fitted within side piece 18 is identical in function and substantially the same in structure having certain portions reversed for obvious reasons.

Within slot 62 is a centrally disposed channel 65 and two stepped apertures 70 each having relieved portions 71. The configuration of each aperture is such as to receive in a close fit stepped pin members 74 each having a lower portion 76 and an enlarged upper portion 78 adapted to nest within complementary bores of the respective apertures as shown more clearly in FIGURE 3. Each of the pin members 74 is internally threaded in portion 76 to receive externally threaded screw portions 73 of members 72 which operate to secure pin members 74 against relative movement with respect to side piece 16. The enlarged diameter portion 78 of pin members 74 is of a length to define a space when the pin members are fully seated slightly greater than the thickness of a latch plate 80. Each pin member 74 includes a head portion 79 adapted to hold plate 80 and is of a length when fully seated so as not to project within the face area of rear bay 12 and interfere with the movement of closure of front bay 38.

Adapted to fit within slot 62 is latch plate 80 having longitudinal slots 94 by which 80 is held against all but sliding movement by the portions 78 of pin members 74.

Plate member 80 in the preferred embodiment is made of stainless steel suitably drilled and formed to include at one end beveled edge 82 and at the other end beveled edge 84 serving to eliminate manufacturing tolerance problems with respect to what otherwise might be sharp edges hindering sliding movements of plate 80 in slot 62. At 40 the end adjoining edge 84 and integral with plate 80 is a pointed portion 86 defining a forward cam surface 88 and a rearward cam surface 90 abutting a cam surface 92 approximately transverse to the longitudinal axis of 80. Further included as an integral part of 80 is a bent out tab portion 98 having a spring stop portion 100 adapted to hold one end of a relatively stiff compression spring 102 against one end of channel 65.

The assembly forming the latching mechanism of the invention is assembled as shown in FIGURE 3 with the plate member 80 held against all but longitudinal movement within slot 62 by the cooperation of slots 94 with portions 78 of pins 74. Spring 102 is held within channel 65 by plate 80 and engagement with 100 and by further engagement with channel 65. It is preferred that spring 102 have a length and characteristics such as to drive plate 80 under considerable force against pins 74 in the position shown in FIGURE 3; the position existing when rear bay 12 does not contain a front bay.

With the latching mechanism of the invention thus described, the operation thereof in performing both the latching and locking functions mentioned above will now be outlined. FIGURE 4 depicts 80 in the position shown in FIGURE 3, the rest position. As front bay 38 is closed the latch pin members thereof including pin 52 will be driven in the arcuate path indicated by the arrow in FIGURES 1 and 4. As 38 continues in the path of closure, member 52 will strike the forward surface 88 of 86 as indicated in FIGURE 5, the slope of which will produce a resultant force driving plate 80 in travel along 62 limited by the diameter of 52 and the line of travel thereof. As 52 moves further inwardly the apex of 86 will be passed and 52 will contact face 90 and face 92, plate 80 being driven downwardly by spring 102 to the position indicated in FIGURE 6. At this point, front bay 38 is latched within rear bay 12

and removal or withdrawal of 38 may be accomplished by pulling outwardly on handles 48 with a force sufficient to result in forces exceeding the spring force of springs 102 in both mechanisms 66 and 68.

In the manner described with respect to FIGURE 1, final movement of closure effected by rotation of arms 30 and 34 operates to drive front bay 38 upwardly to cause pin members to engage contact springs of rear bay 12. FIGURE 7 depicts the movement of latch mechanism 66 caused by the coincident displacement of pin member 52. In the position shown, plate 80 is stopped against further movement in slot 62 by pins 74 engaging the surfaces 95 of apertures 94. As will be apparent from FIGURE 7, the configuration of plate surfaces 86 and 90 taken in conjunction with the disposition of plate 80 positively precludes withdrawal of front bay 38 by blocking forward movement of pin member 52. Front bay 38 is then locked within rear bay 12 and cannot be withdrawn until pin member 52 is returned to the position shown in FIGURE 6 from the position shown in FIGURE 7; which return necessitates movement of handles 30 and 34 to return cams 26 and front bay 38 downwardly to the open position.

Removal of front bay 38 is accomplished in a reverse order from that above described with arms 30 and 34 rotated to drop 38 resulting in spring member 102 driving plate 80 from the position shown in FIGURE 7 to the position shown in FIGURE 6 permitting 38 to be swung outwardly and removed from the assembly 10.

Thus the mechanisms 66 and 68 operate to both latch and lock a plugboard front bay within a plugboard rear bay. The movement of the plate member mechanisms 66 and 68 is limited to approximately the vertical movement of the front bay in the final movement of closure. This distance is also defined by the differences in cam radius and further defined by the spacing between pin and contact spring members with the front bay positioned within the rear bay before closure.

Based upon the above distances and in conjunction with the foregoing teaching, plugboard assemblies may be manufactured or modified to include the advantages of the present invention.

Changes in construction will occur to those skilled in the art and various apparently different modifications and embodiments may be made without departing from the scope of the invention. The matter set forth in the foregoing description and accompanying drawings is offered by way of illustration only.

I claim:

1. An improved plugboard assembly including a rear bay having spring contact members secured therein, a front bay pivotally supported in the face of the rear bay

having pin contact members complementing the spring contact members, the front bay being adapted to swing into the face of the rear bay with pin contact members spaced from the spring contact members by a given distance to permit bay closure, camming means secured to the rear bay operable to drive the front bay upwardly a vertical distance greater than said given distance to cause pin contact members to bear against spring contact members to effect contact therebetween, pin means integral with said front bay, means disposed in the rear bay including latch means having spring means, said latch means being driven upwardly by said pin means as said front bay is closed into said rear bay, and downwardly by said spring means to latch the front bay against withdrawal from said rear bay, the latch means having stops limiting travel thereof to a distance approximating said given distance whereby the front bay is locked within the rear bay following operation of said camming means.

2. The assembly of claim 1, wherein said latch means comprises at least one plate member having a pointed extension defining forward and rearward cam surfaces adapted to cooperate with said pin means to drive said latch means upwardly responsive to inward and outward movements of said front bay, the rearward cam surface operating to cooperate with said pin means to lock said front bay against withdrawal following operation of said camming means.

3. The assembly of claim 2 wherein said plate member includes apertures intersected by said stop means of a length approximating said vertical distance.

4. A latching and locking mechanism for plugboard assemblies of the type having a rear bay and a front bay adapted to be fitted therein and driven in a parallel plane for a given distance to effect contact between contact members supported in each bay, including a latch plate having cam surfaces disposed at one end adapted to cam said plate in a given direction responsive to front bay movement into or out of the rear bay, spring means held between the rear bay and a portion of the latch plate to drive said latch plate in a direction opposite to said given direction and means linking said latch plate to limit movement thereof to a distance approximating said given distance to lock said front bay against withdrawal from said rear bay.
